UNITED STATES PATENT OFFICE.

HENRY W. SHERRILL, OF NEW YORK, N. Y.

DESIGN FOR A SCARF-PIN OR SIMILAR ARTICLE.

No. 38,291.

Specification for Design.

Patented Oct. 23, 1906.

Application filed June 4, 1906. Serial No. 320,213. Term of patent 14 years.

To all whom it may concern:

Be it known that I, HENRY W. SHERRILL, a citizen of the United States, residing at 21-23 Maiden Lane, in the city of New York, in the county and State of New York, have invented a new, original, and ornamental Design for a Scarf-Pin or Similar Article, of which the following is a specification, reference being had to the accompanying drawing, forming a part thereof.

The figure in the drawing is a perspective view showing my design.

I claim—

The ornamental design for a scarf-pin or similar article, as shown.

HENRY W. SHERRILL.

Witnesses:

C. A. GALLAGHER,
H. G. KRETSCH.
